UNITED STATES PATENT OFFICE.

THOMAS LYDWELL ECKERSLEY, OF DANBURY, ESSEX, ENGLAND, ASSIGNOR TO RADIO CORPORATION OF AMERICA, A CORPORATION OF DELAWARE.

AERIALS FOR WIRELESS SIGNALING.

Application filed November 19, 1921, Serial No. 516,236, and in Great Britain January 4, 1921.

The aerials used in wireless signaling are commonly connected to earth though it has before been proposed to connect them to a capacity instead of to earth.

5 The object of this invention is to provide an improved capacity or screen to which an aerial may be connected, and by which the aerial may be rendered more efficient than if it is connected to earth or to a capacity as 10 previously arranged.

According to this invention I so construct the screen that the total electrostatic and electromagnetic action of the aerial and screen together upon the earth is as small as is practically possible. The screen is formed of a 15 number of equal horizontal wires, each of which is at least equal in length to the height of the aerial plus the length of the horizontal part if any of the aerial.

20 The mean distance between any wire and the next to it should be between two and four times the height at which the wires are arranged above the ground, which height should be as small as is practically possible.

25 Since the most important di-electric losses in an earthed aerial are those necessarily introduced by the presence of vegetation at the surface of the earth, the screen should so far as is possible be arranged above the 30 vegetation.

The screen should be supported on metal poles, and suitably insulated from the poles, wooden poles being unsatisfactory on account of di-electric losses.

35 This specification of the screen dimensions is based on the following considerations:

The losses in any aerial may be classified under the following headings:—

40 (1) Losses due to earth currents caused by the currents in the aerial.

(2) Losses due to the presence of imperfect di-electrics in the field of the aerial.

(3) Brush discharge and corona and leakage losses.

45 I find that the use of a screen of wires, as specified largely reduces the losses under headings (1) and (2).

The horizontal electric forces in the earth which produce the earth currents, and hence the earth losses, are caused by the varying currents in the horizontal wires of the aerial.

50 When a screen is used the effect of the currents in the aerial wires in producing earth currents is reduced, on account of the

opposition currents in the wires of the screen. 55 Hence the loss due to these earth currents is always reduced when a suitably designed screen is used.

The screen wires should be arranged so as to annul as nearly as possible the effect 60 on the earth of the aerial currents; for this purpose the wires should be placed so as to cover as uniformly as possible the area underneath the aerial, and should run parallel to the horizontal portions of the aerial if 65 any.

I will now describe in detail the screens to be used with the various forms of aerial, reference being made to the accompanying drawings wherein: Fig. 1, represents the 70 probable distribution of electric force in a plane perpendicular to the wires of an aerial; Fig. 2, is the same when the screen of my invention is used; Fig. 3 shows the probable distribution of potential in the case 75 of Fig. 2; Fig. 4 is a diagram perpendicular to the aerial wires showing the relative location of the aerial and a modified form of screen; Fig. 5 is a longitudinal diagram of the arrangement of Fig. 4; Fig. 5^a is a plan 80 view of an optional arrangement of the screen shown in Fig. 5; Fig. 6 shows the form of screen for use with a fan shaped aerial; Fig. 7 shows the means for balancing differences in electrical length in the 85 screen wires; Fig. 8 shows means for balancing out the effect of unsymmetrical induction in the aerial with regard to the screen; Fig. 9 shows the method of attaching the aerial to a screen for a T aerial.

90 Referring now more particularly to the drawings:

For an aerial of T or Γ form, the screen should be constructed according to the general rules given above as regards length and 95 spacing of the wires; these should be parallel to the horizontal wires of the aerial and the breadth of the screen should be equal to the breadth of the aerial plus twice its height.

100 The addition of wires in the screen beyond a certain number cannot reduce the resistance appreciably, so that it is not economical to use more than a specified number of wires.

105 This number need not exceed the number obtained by dividing the breadth of the screen by twice the height of the screen,

while the number should not be so small that the distance between any wire and the next is greater than four times the height of the screen.

5 The probable distribution of electric force in a plane perpendicular to the wires of the aerial and screen is shown in Figures 1 and 2 of the accompanying drawings. In Figures 1 and 2, A A are the wires of the aerial and in Figure 2 S S are the wires of the screen.

This distribution is practically the same as that due to equal and opposite charges on aerial and screen.

15 The electric force leaking through only depends on the ratio of the distance between adjacent screen wires to the height thereof above the ground.

The vertical electric forces at the surface 20 of the earth are responsible for the losses (2) above.

When a screen is used the induced charges 25 on it intercept a large proportion of the vertical force, and these losses are consequently reduced.

These considerations, which have been confirmed experimentally, substantiate the claim that an aerial connected to a screen as specified in the opening paragraph is materially more efficient than the same aerial 30 connected to earth. As long as the breadth of the screen and the same spacing ratio conform with the rules given above the losses are practically independent of the height.

35 The height of the screen is therefore determined almost solely by considerations of cost and practicability.

The cost of the screen will be great if it is too high or too low; for the former case 40 involves the use of excessively high supports, and the latter the use of an excessive number of wires. Hence the screen should be at either the minimum practical height or at such a height as will reduce the cost of the 45 screen to its minimum, so long as this does not involve a serious reduction of the effective radiating height of the aerial.

In order to prevent the mean potential of the system consisting of the screen and aerial 50 differing largely from that of the earth, a point on the loading coil may be connected to earth. This point should be the node of potential of the oscillation in the system, for when such a nodal point is connected to 55 earth the high frequency oscillations are unaltered and no increase of resistance occurs. The probable distribution of potential throughout the system is shown in Figure 3.

Slight modifications may be made in the 60 height and spacing ratio to suit special conditions.

(1) If owing to want of space the screen cannot be extended beyond the aerial an amount equal to the height of the aerial the 65 outside and end wires may be raised so as

to reduce the stray leakage field over the edge as shown in Figures 4 and 5 which are a section and side view respectively.

(2) The screen wires may be forked at the end where the total electric field is most 70 intense, so as to give better shielding in the more important part of the screen as shown in Fig. 5a.

(3) If the screen has to pass over buildings, etc. the spacing ratio may be reduced in 75 the neighborhood to suit the effective height of the screen over the building.

The rules for the arrangement of the screen to be used with an umbrella or radial type aerial are similar to those for T or 80 F shaped aerial screen.

The screen should consist of a number of wires in a horizontal plane and radiating from a point beneath the centre of the aerial, and the spread of the wires should be 85 sufficiently great to cover the whole of the ground beneath the aerial. The length of each wire should be equal to the radius of the aerial plus its height, and spacing of the wires should be such that the distance between the middle points of two adjacent wires should be between two and four times 90 the height of the screen above the earth, the outer portions of the wires being forked if the larger distance be employed. 95

In the case of a fan shaped aerial in which the angle of the fan is small, say less than 45 degrees, it is inadvisable to have the screen in the form of a fan. It should be a parallel wire screen of the same form as that used 100 with an ordinary T type aerial. Alternatively it should be of the form shown in Figure 6. In this figure the aerial wires are carried by three masts M and the screen is formed of wires S S radiating from a 105 centre the outside wires being parallel to the outside wires of the aerial. The distance between each outside wire S and the projection on the plane of the screen of the outside wire A should be as great as the 110 height of the aerial.

For a vertical aerial having no horizontal wires the screen should consist of wires of equal length radiating at equal angles from the aerial as a centre, the length of each 115 wire being equal to the height of the aerial and the distance between the middle point of any wire and the next being two to four times the height of the screen; as before if the larger ratio be employed the outer 120 portions of the wires should be forked.

The screen wires may form a system possessing one or more natural periods of oscillations of its own, apart from the oscillations in the aerial. If the working period 125 of the aerial is at or near one of these periods oscillations may be set up in the screen which do no useful work and only absorb energy. In order to eliminate these oscillations the potential nodes of all of them 130

should, if possible, be at the point at which all the screen wires join, and the aerial should then be attached at this point so that interaction between the aerial system and the system formed by the screen wires is eliminated.

This can be done:—

(1) By making the length of the wires as nearly equal as possible.

(2) By balancing up the small effective electrical differences of length by inserting as shown in Figure 7 suitable inductance coils L in each wire or group of wires of the screen, which is here shown divided into four sections or groups.

In cases where the aerial wires are placed unsymmetrically with respect to the circuits which are formed by the screen wires and in which the undesirable oscillation is taking place, the currents in the aerial may induce in those circuits E. M. F.'s which will produce oscillations even when the aerial is attached at the node. In this case the effect of these E. M. F.'s can be partly annulled by shifting the point of attachment of the aerial away from the anode. This can be done by a slight adjustment of the inductances referred to above, or by providing a suitable inductive or capacitive coupling between the aerial and the circuit in which the oscillations are taking place so as to balance out the effect of the unsymmetrical induction. Figure 8 shows a coil P connected to the aerial and coupled to a coil Q connected to the screen.

The natural period of the screen oscillations may be removed from the working point (probably below the natural period of the aerial) by connecting the ends of the screen together with a wire, thus avoiding interaction of the systems.

This has the advantage that circulating currents may be induced in the closed circuits in the screen formed by this wire; although the resistance may be largely reduced in this way it is not so effective as balancing, though it is simpler.

To eliminate the effect of the oscillations which may occur in the circuits formed by the screen wires the point of attachment of the aerial to the screen may be earthed thereby forcing this point to be a node of potential, but this should only be done when the wave length employed is such that there is no danger of the oscillations due to the screen itself acting as a T aerial interfering with the main oscillations.

When the aerial is of T form with a screen under each arm of the T the best way to balance out the oscillation from end to end of the screen is to insert a small inductance between the two halves of the screen and to find the node and attach the aerial there as shown in Figure 9.

Each half of the screen should be bal-

anced up separately as indicated above for F aerials.

This has the advantage that not only is it easy to find the node but oscillations across the screen are eliminated and the natural oscillations of the aerial and screen are favored.

Having described my invention, what I claim is:

1. An aerial system consisting of the combination of a conductively related aerial, aerial inductance, and screen, said screen being insulated from the earth and composed of a plurality of substantially horizontal wires each of which is of a length at least equal to the height of the aerial above the ground plus the length of the vertical projection of the aerial, and each of which is spaced from the next adjacent wire by a mean distance of between two and four times the height of said screen above the ground, the outer portions of said screen being raised above the remaining portions.

2. An aerial system consisting of the combination of a conductively related aerial, output inductance, and screen, said screen being insulated from the earth and composed of a plurality of substantially horizontal wires each of which is of a length at least equal to the height of the aerial above the ground plus the length of the vertical projection of the aerial, the outer portions of said screen being raised above the remaining portions.

3. An aerial system consisting of the combination of a conductively related aerial, output inductance, and screen, said screen being insulated from the earth and composed of a plurality of substantially horizontal wires each of which is of a length at least equal to the height of the aerial above the ground plus the length of the vertical projection of the aerial, the outer portions of said wires being forked substantially as described, and the outer portions of said screen being raised above the remaining portions.

4. The combination with an aerial of a screen and a plurality of inductances, said screen being suspended above the earth and insulated therefrom and composed of a plurality of wires which are horizontal throughout the greater portion thereof, and of a length at least as great as the vertical projection of said aerial plus the mean height of said aerial above the ground, and spaced a distance between two and four times their height from the earth, said screen being of a width at least as great as the width of the projection of said aerial upon the earth plus the height of said aerial above the ground, and said inductances being arranged to compensate for the differences in electrical length of the various wires composing said screen.

5. The combination with an aerial of a

- screen for aiding the radiation of electro-
magnetic waves and consisting of a plurality
of horizontal wires each of which is of a
length at least equal to the height of the
aerial above the ground plus the length of the
vertical projection of the aerial, and in-
ductances inserted in the screen for compen-
sating for the differences in electrical length
of said wires, said screen being conductively
connected to said aerial at the potential
node point of said screen.
6. An aerial system consisting of the com-
bination of a conductively related aerial,
output inductance, screen, and ground con-
nection, said screen being insulated from the
earth and composed of a plurality of sub-
stantially horizontal wires, each of which is
of a length at least equal to the height
of the aerial above the ground plus the
length of the vertical projection of the aerial, and said ground connection being made at the potential node of said output inductance.
7. An aerial system consisting of the com-
bination of a conductively related aerial, out-
put inductance, screen, and ground connec-
tion, said screen being insulated from the
earth and composed of a plurality of sub-
stantially horizontal wires, each of which is
of a length at least equal to the height of the
aerial above the ground plus the length of the
vertical projection of the aerial, the outer
portions of said screen being raised
above the remaining portions, and said
ground connection being made at the poten-
tial node of said output inductance.

THOMAS LYDWELL ECKERSLEY.
